UNITED STATES PATENT OFFICE.

HENRY F. COX, OF JERSEY CITY, NEW JERSEY, AND ALEXANDER MILLAR, OF NEW YORK,
N. Y., ASSIGNEES TO HENRY F. COX.

MACHINERY FOR CUTTING CORKS.

Specification of Letters Patent No. 33,122, dated August 20, 1861.

To all whom it may concern:

Be it known that we, HENRY F. Cox, of Jersey City, State of New Jersey, and ALEXANDER MILLAR, of the city, county, and State of New York, have invented certain new and useful Improvements in Machinery for Cutting Corks; and we do hereby declare that the following is a full, clear, and exact description of the same, reference being made to the annexed drawing, making a part of this specification, in which—

Figure 1 is an end view or elevation. Fig. 2 is a top or plan view. Fig. 3 is a side elevation. Figs. 6 and 7 are of parts in detail.

Similar letters indicate similar parts throughout the figures.

My invention is an improvement in that class of cork-cutting machines by which a number of corks may be cut at one and the same time out of a slab or sheet of the cork-wood, and it consists, firstly, in the manner whereby the clamps, around which the cutters revolve, are made to press upon and hold the cork while it is being cut; secondly, in the peculiar construction of the cutting parts, and thirdly, in the general arrangements whereby the machine may be as economically employed in the cutting of short corks as upon long ones.

In this class of machines, as hitherto constructed, the clamping pieces have been attached to the cutter stocks, being inserted in the ends thereof and made to press upon the cork by a coiled spring within the stock acting to throw the clamp out. This spring must, at the commencement of the cutting, be stiff enough to hold the cork-wood properly in its place, and as, by the advance of the cutters, it becomes of course still further compressed, it soon crushes down the elastic cork, whereby the cutters are required to work as they progress in material of increasing density. This however is not the only evil, for the pressure throws the cork to one side and hence it bears against the cutters with considerable force, making it necessary that more power should be employed to drive the machine than was at first necessary, on account of the lateral friction of the cutters as well as the denser character of the material upon which they come to operate. In the cutting of large flat corks, such as for pickle jars or for bungs, this deflective action is of but little importance,

but when making long and slender ones, suitable for claret bottles, the crushing down of the spring clamps is so great as often to destroy the cork. In order to avoid the necessity of first cutting the cork-wood into blanks or squares for single corks, or to secure rapid working if they are not so cut at first, the cutters must be so constructed that they will clear out a path for themselves to travel in out of contact with any more of the wood than is actually necessary. These machines have also been defective in another particular, viz. as much time has been occupied in cutting a short cork as was required for the longest, since the machines have been constructed for the travel necessary to cut a cork of maximum length and have not been capable of such adjustment that the travel could be made only to the distance required when operating on thinner sheets of material. All of these defects are obviated by the improvements which we have made, as will be seen from the following description of the construction and operation thereof.

The cutters and clamps are arranged across one end of the frame work of the machine, in a vertical position, and over the supporting table, as seen in Figs. 1 and 2, wherein M represents the spindles or revolving stocks for carrying the cutters, the letter I the fixed clamps passing through said spindles, and N N' the pair of cutters to each spindle. Beneath these rests the table E which has nuts F and screw bolts, as shown, in order that the table may be raised or lowered. The cutter spindles M are held like drill-stocks in a frame as seen at (o) in the several figures. This is attached to fixed slides P in such manner that it can be moved up and down. These spindles are hollow, and the clamp rods I pass up through them and each rod is suspended at its top end by a knob resting in the forked end of a lever or arm, K, which projects from a cross shaft (r) resting upon the main frame. Upon the top of each clamp-rod there presses a feather spring J tending constantly to force it downward. At the lower end of each rod is a round clamp plate I' roughened on that surface which presses upon the cork so as thereby to maintain a secure hold. The use of the levers K is for raising the clamps to free the cork and to make room to insert a fresh piece of corkwood.

- 5 An arm (*u*) is attached to the cross shaft (*r*) and this is again connected with a second lever (*t*) beneath, the end of which is struck by a post (*s*) affixed to the sliding frame (*o*), so that when the latter rises to carry up the cutters this post will strike (*t*) and raise also the clamps. The frame carrying the cutter spindles is caused to be raised and lowered by two cams (*h*) and (*g*) 10 revolving upon a cross shaft (*f*) at the back part of the frame, and acting upon a system of adjustable levers and lift rods by which the two are connected together. The cam (*g*) is for raising the frame (*o*) and the cam (*h*) for depressing it. These cams act 15 upon opposite sides of a vertical post (*i*) through a slot in which the cam shaft passes, as shown in Fig. 3. The post (*i*) is connected to one end of a lever of the first kind (*m*), which is again connected to another lever (*p*) by a link (*n*), and this latter to the frame (*o*) by link (*q*) which has adjustments for varying its length. There is also 20 an adjustment for increasing the throw of the levers viz., by slots or holes (*m'*) and (*p'*) by which the link (*n*) may be shifted to or from their respective fulcras. 25 The object of lengthening or shortening the levers is to give more or less travel to the frame (*o*) according to the length of the corks to be cut and thickness of corkwood. The object of the adjustable link (*q*) is to 30 set the frame so as to start always from a given point in its downward motion, which 35 it would not otherwise do when the extent of the arc of the motion of the levers was changed. 40 The frame (*o*) carrying the cutter stocks may be made to descend, when cutting a short cork, at the same rate of speed as when cutting a long one, by taking off the gear wheels (*b*) and (*c*) which transmit the motion from the main shaft *C* to the shaft (*f*), and substituting for them others having the 45 number of their teeth relatively different, and thus the speed of the shaft (*f*) may be varied when the proportion of the ends of the adjustable levers to each other has been changed. 50 The cutter spindles are shown as being 55 geared together by toothed wheels *M'*, the object of which is to keep the cutters of one spindle from interfering with those of the next, by causing them to keep always a certain distance from each other. Thus considerable saving may be effected of the corkwood, since the cutter stocks may be placed so closely together that the path of the cutters will intersect each other, as seen in Fig. 60 6, so that the corks cut out will be separated only by the width of the groove formed by the thickness of one set of cutters, in consequence of the cutters of the next spindle traveling partly in this groove, and so on 65 throughout the series, whereas were the spin-

dles so far apart that the paths of the cutters will not intersect, there would be left not only a stratum of wood but the thickness also of an additional cutter groove. These spindles are driven by belts *Q* passing 70 over a drum *R*, the shaft of which rests upon two pillars *S* rising from around the main driving shaft, and then a weight *W* applied to act upon them, as shown, will keep the said belts in proper tension at all 75 times.

The cutters are of peculiar construction. These are seen at *N* and *N'* in the several figures and are represented as enlarged in Fig. 7. Two or more may be carried by 80 each spindle. As shown in the drawings there are but two, being the least that will effect the cutting properly. Each cutter consists of two acting parts viz. a cutting blade and a grub. The blades precede the grub. 85 The lower end of each cutter terminates in a thin flat blade, as shown in Figs. 1, 3 and 7. A little above is seen the grubbing point— at (*r'*) and (*g'*) of Fig. 7. This is formed upon one of the cutters by beveling the tool 90 as seen in the enlarged views at (*r'*) up to the blade, and squaring the point so formed. The opposite cutter is differently formed at this part by grooving out the edge of the grub and thus forming a short second blade, 95 as at (*g'*) Fig. 7. It will be seen that the position of these tools is such that the points of the two blades on each spindle will not follow each other in the same track but will describe two circles of different diameters and concentric. Thus as they penetrate the cork-wood two thin circular incisions will thereby be made, leaving a narrow stratum of cork between of the thickness of the cutter shank. As the blades penetrate, 100 the point of the grub (*g'*) will come upon the cork left in this annular space and begin to grub it out, but leaving it in a ridge which the square ended grub (*r'*) further reduces, and thus the cork so detached is discharged. 105

The operation will be as follows—The cam (*g*) being brought around so as to be under the roller (*h*) the frame (*o*) will then be at its full height. The cutters and clamps all being thus brought up, the link (*n*) is 115 now to be so set in the slot in the levers (*m*) and (*p*) as to produce the proper degree of descent, the cutters should have to pass through a given thickness of corkwood. The link (*q* and *q'*) is then to be adjusted 120 for length so as to raise the frame (*o*) to its full height as the given starting point for cutting all corkwood whatever be its thickness, and the table *E* must be raised so as to bring the top of the cork blocks up to the 125 clamps. The gear wheels (*b*) and (*c*) should now be adjusted, using a set which will give as rapid downward travel to the frame (*o*) as is consistent with the proper action of the cutters, and it will be evident 130

that when the levers are at any time adjusted to give a greater length of travel, the speed of the shaft (*f*) will have to be increased in order to afford the same speed 5 of travel to the said frame. These adjustments being properly made, a strip of cork-wood of suitable thickness for the desired length of the cork is to be placed upon the table and the machine put in motion. As 10 soon as the cam (*g*) clears the roller (*k*) the arms *K* will be released, for the post (*s*) will drop by reason of the frame beginning to descend; the springs *J* will thus force down the clamp rods upon the cork. The 15 cutters, being now in rapid revolution, penetrate the material, and are caused to descend gradually by the cam (*h*) acting to press down the rod (*i*). The thin blades first inscribe two concentric circles, the grubs fol- 20 low as already described, and complete the excavation, leaving finally a complete cork under each clamp detached from the cork-block. The preceding edge of the cam (*g*) has now come around to the roller (*k*) while 25 (*h*) has got clear of its lower roller (*l*). The whole row of spindles will now be lifted suddenly so that their cutters will be clear of the corks. This is done by means of a weight or spring applied at the opposite end 30 of the lever (*p*) upon a rod *A'*. The upward motion of the frame (*o*) will be arrested when the pin (*s*) strikes the lever (*t*), the springs *J* resisting the movement of the arms *K*. The cam (*g*) now strikes (*k*) 35 thus raising the frame (*o*) still higher, but to a slight degree only, and carrying with it the clamp rods *I* through the lifting lever or arms *K*. This last motion releases the cork and cork-wood, when the whole may be 40 drawn off the table and a new slip inserted,

time being allowed for this while the cam (*g*) is moving past the roller (*k*). At *G* is a facing of wood upon *E* to allow the cutters to penetrate slightly so as to insure that they pass completely through the cork-wood. 45 Different diameters of corks can be produced by spreading apart or bringing nearer together the cutters, which may be accomplished by well known devices, such as screwing a new cutter head to the spindles 50 of the required dimension &c.

We claim—

1. So combining the fixed clamps with the spindles and cutters revolving around them, that the latter can be both revolved, and 55 raised and lowered, without imparting motion to the clamps, substantially in the manner and for the purposes set forth.

2. The cutters so formed as to make, in the first instance, two annular and concentric incisions and then grub out the cork-wood left detached by said cutters, substantially in the manner herein set forth. 60

3. The arrangement, as described, of the adjustable levers and links, and their combination with the spindle frame and the driving cams, for the purpose of producing the different degrees of travel required of the spindle frame for cutting corks of various lengths, and of enabling the said frame 65 to be always started from a given point, as set forth herein. 70

In testimony whereof we have hereunto subscribed our names.

HENRY F. COX.
ALEXANDER MILLAR.
